PACKAGED GAS COMPRESSOR UNIT

Jay L. Cannon, Jr., Hunters Creek, Tex., assignor to
Southwest Industries, Inc., Houston, Tex., a corpora-
tion of Texas

Application January 4, 1957, Serial No. 44,405

Term of patent 14 years

(Cl. D65—1)

Fig. 1.

Fig. 2.

Figure 1 is a side perspective view of a packaged gas compressor unit, embodying my new design; and

Figure 2 is a perspective view of such unit taken from the opposite side.

I claim:

The ornamental design for a packaged gas compressor unit, substantially as shown.
